ABSTRACT: The device disclosed provides a punch and die set in which accurate locating guides are provided to match the punch to the die perfectly to avoid damaging the cutting edges. The shearing operation on soft rubber requires an absolute match between punch and die without the clearance usually used in other forms of trimming dies. This has especial utility in shearing operations on soft rubber and the like.

DIE SET

STATEMENT OF INVENTION

This invention relates to punch and die sets and, more particularly, to punch and die sets with an improved aligning means especially adapted to be used in punching such soft resilient material as soft rubber.

OBJECTS OF THE INVENTION

It is an object of the present invention to provide an improved punch and die set.

Another object of the invention is to provide a punch and die set that is automatically aligned when placed in operating position.

BRIEF DESCRIPTION OF DRAWINGS

FIG. 1 is a side view of the die set according to the invention.

FIG. 2 is a front view of the die set.

FIG. 3 is a top view of the die block.

FIG. 4 is a front view of the die support block.

FIG. 5 is a top view of the punch and die set.

FIG. 6 is a view similar to FIG. 1 of the die set with certain other parts added.

DETAILED DESCRIPTION OF THE DRAWINGS

Now with more particular reference to the drawings, the die holder 10 is shown with the punch holder 11 supported above it. The die holder 10 may be supported on the anvil of a punch press or the like and the punch holder 11 may be attached to the ram of the punch press by means of the member 27. The punch holder 11 will normally have a punch 19 fixed to it and the die block which is supported on a retractable slide 12 is slidably supported on the die holder 10 by gib 14 which engage grooves 26 in the bottom surface of the retractable slide 12. The retractable slide 12 engages the microswitch 25 which is fixed to the rear end of the die holder 10 and which may be connected to the actuating mechanism of the press so that the press cannot be actuated until the slide is in engagement with the die holder 10.

The slide 12 will have the die 28 supported on the slide 12 which will move under the punch 19 which has protrusions 29 and 30 fixed to it which are adapted to enter similar recesses in the die. The advantages and versatility of the slide retracting die sets is demonstrated when the retracted slide feeds the stock 35 for subsequent operations without aid from a stock feeder.

One of the most difficult materials to punch in a trimming die is soft rubber materials. The retracting slide is important because the formed rubber has to be placed accurately into the die cavity and visual inspection is necessary. Razor sharp cutting edges are also important since the rubber stretches and the part is damaged if the cutting edges are not extremely sharp.

The punch is accurately matched to the die by means of the bushings 22 which have an upper part 30 which has a cylindrical bore 13 therein. The bushings have the lower part 32 which has a half-cylindrical bore 33 which is a continuation of the bore 31. The two integral parts 31 and 32 of the bushing are fixed to punch holder 11. The half cylindrical part 32 of the bushings extends down below the upper cylindrical part 31 of the posts 121 when the ram of the press is in the up position. Thus the top of the post can move under the end of the upper

part 30 of the bushing and into nesting engagement with the half cylindrical surface 33. In this position, the posts will be in alignment with the cylindrical hollow 31 so that the punch can descend accurately. The slide has a handle 9 with sides 20 fixed to its front end. The die is shown with a strip of rubber material 35 which is to be punched. The rubber material is slid over the stationary die 18. Thus when the operator moves the handle 9 rearward until the posts 12 seat in the half cylindrical surface 33 and the stop 13 engages the front of the die holder, the punches 28 and 30 will be in exact alignment with the corresponding openings in the die 18. Thus when the operator grasps handle 20 and moves block 12 to bring stop 13 against the front of the die holder, the catch 5 engages the stock and moves it together with the main slide 12 to the initial operating position. The block will, at this point, engage the microswitch 25 so that the press can operate and punch a hole in the material 35.

The embodiments of the invention in which an exclusive property or privilege is claimed are defined as follows:

We claim:

1. A die set comprising
a die holder, adapted to be supported on the anvil of a machine,
a die block means slidably supported on said die holder,
posts fixed to said die block and extending upwardly
therefrom,
a punch holder,
means on said holder for attaching it to a machine ram,
a punch member attached to said punch holder,
bushings on said punch holder,
said die block being adapted to move toward said punch
holder and said posts being adapted to be received in said
bushings whereby said punch member is guided into said
die,
said bushings having a first portion with a cylindrical hollow
bore therethrough terminating slightly above said posts
when said punch is in its upward position,
said bushings each having a second portion integral with
said first portion with a half cylinder shaped bore forming
a continuation of said cylindrical bore,
said die holder being adapted to slide relative to said punch
holder bringing said posts into nesting engagement with
said half cylindrical portion whereby said posts are posi-
tively guided into said bushings when said punch is moved
toward said die and said die is moved precisely into said
punch.

2. The die set recited in claim 1 wherein said means sup-
porting said die block on said die holder comprises
gib means on the said die block and slidably engaging each
other,
and laterally disposed upwardly extending guide means on
said die holder slidably engaging means on the sides of
said die block.

3. The die set recited in claim 1 wherein means is disposed
on said die holder to limit the movement of said posts from
said bushings and a means is provided to disable said press
while said die block is moved to bring said posts away from
said bushings.

4. The die set recited in claim 3 wherein catch means are
provided on said slide adapted to advance a continuous strip
of material along said slide each time said slide is pulled out
from said die holder and returned into said die holder.

5. The die set recited in claim 4 wherein said slide is adapted
to be oscillated whereby said material can be fed from a roll by
said feeding means being adapted to feed precise amounts of
said material.
